UNITED STATES PATENT OFFICE

WILHELM REINERS AND GUSTAV KAHLISCH, OF MUNICH-GLADBACH, GERMANY, AS
SIGNORS TO W. SCHLAFHORST & CO., OF MUNICH-GLADBACH, GERMANY, A COR-
PORATION OF GERMANY

WARPING FRAME

Application filed June 10, 1929, Serial No. 369,845, and in Germany December 19, 1928.

The invention relates to improvements in warping frames in which the warp beam is driven by frictional surface contact with a drum. Such warping frames often show the following two drawbacks. If the body of warp yarn on the beam becomes untrue owing to irregular winding-on at the beginning or from other causes, the beam will jump on the drum intended to drive it, and this jumping is instrumental in still further accentuating the untrue shape of the beam. The second drawback is that the pressure of the beam against the drum must vary according to the quality of the warp yarn.

In order to obtain the contact pressure required for the purpose of winding the warp yarn onto the warp beam with the required firmness, it has hitherto been usual to employ an arrangement of levers and dead weights which also suffices as a rule. However, the lever and weight arrangement cannot prevent the beam from jumping. Jumping of the beam can only be prevented by placing into the path of the displacement of the beam caused by the increase of its diameter, a controlled pressure, namely a braking pressure. Efforts have been made to obtain this braking pressure by braking the displacement of the beam bearings caused by the continually growing diameter of the beam, but if the braking devices on the two beam bearings are not adjusted exactly alike, one bearing will give way more readily than the other, and the result is a conical shape of the yarn body of the beam.

The present invention has for its object the elimination of this fault, this aim being arrived at by subdividing the additional contact pressure necessary for the prevention of the jumping and for the formation of a firm yarn body in such a way that one component takes over the task of preventing the jumping, and the other one that of ensuring the firm yarn body. The additional pressure to prevent the jumping is intended to be caused by a braking device placed into the path of the displacement of the beam, whilst the additional contact pressure for the firm yarn body emanates from a place common to both arms supporting the beam at either end respective-

ly in order to transmit the contact pressure evenly and positively to both beam arms. For this purpose, the two arms supporting the warp beam are both connected to one and the same shaft arranged in the warping frame by means of rigid or flexible arrangements such as for instance connecting rods, toothed racks, chains or ropes, the aforesaid shaft being braked to the extent required by the additional surface contact desired. The braking power exerted on the shaft is therefore evenly transmitted to both beam arms by means of the arrangement mentioned. The braking power to be exerted on the shaft can be generated by means of dead weights, one or more brakes of any known kind, preferably adjustable, spring or dead weighted, or other arrangement suitable for the purpose.

In Figs. 1 and 2 we show an example of the practical application of the invention in rough outlines and seen from two different points.

n, k, h is the braking device placed into the path of the displacement of the beam and the resistance of which is intended to prevent the beam from jumping.

c are the two arms supporting the beam at either end and at the ends of which the beam is supported in bearings. 1 is a shaft supported in the machine framing, and which is connected to the beam arms *c* by means of a pair of flexible members 3 (chains, ropes, belts, or the like), one end of each of which is attached to the beam arms *c* at the point 5, said point 5 comprising a hook, the flexible organs being passed under pulleys 4, and the other ends being wrapped onto pulleys or discs or the like fixed on shaft 1. Shaft 1 may be fitted with a plate or band brake, or it may carry a drum or disc or scroll 6 onto which the pulley member 7 of a weight or spring power store is wound. It will thus be observed that the resistance of shaft 1 militates against a displacement of the warp beam *a*, the resistance being evenly distributed on both beam arms.

To permit of an easy exchange of warp beams, the shaft 1 may be fitted with a toothed wheel 10 into which engages a smaller pinion 11 connected to a hand wheel 100.

12. When the flexible members 3 have been detached from the hooks 5 on the beam arms, they can be suspended at point 13 in order to be ready to hand when required. For detaching the drawing elements 3 from the hooks 5, it is necessary to turn the shaft a little further.

13. If a weight is used as a resistance, it is advisable to fix on the shaft a ratchet wheel 8 to act in connection with the pawl 9 to hold the weight suspended in the higher position.

14. What we claim and desire to secure by Letters Patent is:

15. 1. A warping frame with a warp beam driven by surface friction including a beaming drum, a warp beam driven from said drum by surface friction, a plurality of beam arms carrying said warp beam, means for producing a pressure of the warp beam against said beaming drum comprising a separate shaft, a torsional resistance means on said shaft and a flexible tension member connecting each of said beam arms with said shaft.

16. 2. A warping frame with a warp beam driven by surface friction including a beaming drum, a warp beam driven from said drum by surface friction, a plurality of beam arms carrying said warp beam, means for producing a pressure of the warp beam against said beaming drum comprising a separate shaft, a torsional resistance means on said shaft and a flexible tension member connecting each of said beam arms with said shaft, and means for manually turning said shaft for releasing said warp beam from said torsional resistance.

17. 3. A warping frame with a warp beam driven by surface friction including a beaming drum, a warp beam driven from said drum by surface friction, a plurality of beam arms carrying said warp beam, means for producing a pressure of the warp beam against said beaming drum comprising a separate shaft, a torsional resistance means on said shaft and a flexible tension member connecting each of said beam arms with said shaft, means for manually turning said shaft for releasing said warp beam from said torsional resistance, and means for holding said shaft in said last-named position.

18. 4. A warp frame with a warp beam driven by surface friction including a beaming drum, a warp beam driven from said drum by surface friction, a plurality of beam arms carrying said warp beam, means for producing a pressure of the warp beam against said beaming drum comprising a shaft, a weight connected to said shaft tending to turn the same and a flexible tension member connecting each of said beam arms with said shaft.

19. 5. A warping frame with a warp beam driven by surface friction including a beaming drum, a warp beam driven from said drum by surface friction, a plurality of beam

20. arms carrying said warp beam, means for producing a pressure of the warp beam against said beaming drum comprising a separate shaft, a torsional resistance means on said shaft, flexible members, each of said beam arms having one end of one of said flexible members connected thereto, the other end of each of said flexible members being wound on said separate shaft.

21. 6. A warping frame with a warp beam driven by surface friction, including a beaming drum, a warp beam driven from said drum by surface friction, means for producing a pressure of the warp beam against said beaming drum comprising a flexible tension member connected at one end to said warp beam and torsional resistance means connected to the other end of said tension member.

22. 7. A warping frame with a warp beam driven by surface friction, including a beaming drum, a warp beam driven from said drum by surface friction, means for producing a pressure of the warp beam against said beaming drum comprising a flexible tension member connected at one end to said warp beam and a weight connected to the other end of said tension member, and means for preventing jumping of the beaming drum comprising a friction brake member connected to said beaming drum.

23. 8. A warping frame with a warp beam driven by surface friction, including a beaming drum, a warp beam driven from said drum by surface friction, a plurality of beam arms carrying said warp beam, means for producing a pressure of the warp beam against said beaming drum comprising a shaft, a flexible tension member, one end of which is wound on said shaft, a weight supported from the other end of said tension member, and connections between said shaft and each of said beam arms.

24. The foregoing specification signed at Cologne, Germany, this 24th day of May, 1929.
